LIQUID DISPENSER

William E. Turner, Summerville, Ga.

Application June 1, 1945, Serial No. 597,062

6 Claims. (Cl. 222—482)

1

My present invention, in its broad aspect, has reference to improvements in liquid dispensing dispensers of the type having a container for the liquid to be dispensed and a removable closure cap which is a part of and supports my improved liquid dispensing device. More particularly, it is my purpose to provide a liquid dispenser formed with a cap part in which the valve is mounted to open and close both an air inlet and a liquid outlet leading respectively to a liquid outlet tube and an air inlet tube; the operating structure of the valve being located between the liquid outlet tube and the air inlet tube to be handily operated, and these tubes coming together at a point where provision is made for detachably connecting a nozzle which also has a liquid outlet and an air inlet conduit registering therewith. I also provide air venting means in the air inlet in case the same should become flooded by the liquid or otherwise clogged, and the operating mechanism for the valve is simple, sturdy, dependable and practical, and means are provided for holding the valve in open position against the tension of a spring closure means.

Other and equally important objects and advantages of my invention will be apparent from the following description and drawings, and it is pointed out that changes in form, size, shape, materials, and construction and arrangement of parts is permissible and within the purview of my broad inventive concept and the scope of the appended claims.

In the drawings wherein I have illustrated a preferred form of my invention:

Figure 1 is a vertical section and shows the valve in open position for dispensing liquid from a container;

Figure 2 is a section on the line 2—2 of Figure 1;

Figure 3 is a section on the line 3—3 of Figure 1;

Figure 4 is a section on the line 4—4 of Figure 1;

Figure 5 is a side elevation, partly in section, showing the valve in closed position;

Figure 6 is a section on the line 6—6 of Figure 5;

Figure 7 is a section on the line 7—7 of Figure 5;

Figure 8 is a section through the nozzle showing the manner of attaching the same to the dispensing device;

Figure 9 is a side elevation, with the dispensing device in section, of a modified form of my invention;

2

Figure 10 is a top plan view of the dispensing device of Figure 9;

Figure 11 is a section on the line 11—11 of Figure 9;

5 Figure 12 is a detail view of the adjustable stop or rest for supporting the receptacle during a filling operation, and

Figure 13 is a section on the line 13—13 of Figure 12.

10 In the drawings wherein like characters of reference are used to designate like or similar parts throughout the several views:

The numeral 1 designates a liquid container of the type having a threaded open top 2. My dispensing device is attached to and forms a covering for the container 1 and has a circular base 3 with an internally threaded annular flange 4 which is attached to top 2 as shown in Figures 1, 5 and 9. Formed on a boss 5 on the base 3 is a spout 6 the bore of which leads through the top as at 7 for dispensing the liquid. The boss 5 has a bore adjacent the spout through which is journaled the stem 8 of a valve 9. The valve head consists of a circular plate 10 and a circular leak-proof washer 11 held on the stem by a screw 12. The valve head is of sufficient diameter to close the outlet to the nozzle and to close the end 13 of an air inlet tube 14 leading into the container through the base. The tube is spaced 15 from the nozzle throughout a major part of its length and is then bent toward the nozzle as at 16 and leads into an air inlet conduit 16 formed in the end of the nozzle adjacent its bore. The tube has an opening 17 adjacent the base, normally closed by a spherical valve head 18 on the pivoted lever 19 which is carried by the arms of a bracket 20 and is provided with a spring 20a to normally hold the valve closed unless pressed on the end 21. The purpose of the opening 17 and 20 valve 18 is to relieve the air inlet in case it becomes filled with liquid or becomes clogged for any reason.

The boss 5 has a circular cavity 22 in which is packing 22a to prevent leakage about the valve 23 stem 8. A coil spring 23 about the valve stem and seating in the cup 24 fixed on the end of the valve stem and normally holds the valve closed, and a rotatable latch plate 25 mounted on the attaching screw 26 at the end of the stem and 27 engages in notches 27 in a web 28 on the spout to hold the valve open. The latch plate has a handle 29 and a notch 30 to permit movement of the valve from closed to open position. A stop lug 31 on the end of the latch plate limits its 35 rotatable movement.

The end of the spout is formed with a threaded annular flange 32 against which bears a leak-proof washer 33—see Figure 8—to attach a nozzle 34 removably thereto. The nozzle also has an air inlet 35 and a fluid outlet, and has a stop flange 36 to prevent disengagement of a threaded knurled coupling collar 37 for coupling the nozzle to the spout. On the nozzle 34 is adjustably mounted a stop or rest plate 38 having an end flange 39 and mounted by the screw 40 whereby to contact and support the nozzle in a filler opening (not shown) while filling a receptacle or the like from the container.

As shown in Figures 9, 10, 11 and 17, my device may be used without a valve in which case the nozzle 41 is formed with a side enlargement 42 from end to end containing the air inlet conduit 43. Both the air inlet conduit 43 and the fluid outlet bore are tapered as at 44 to the end of the nozzle and the end is circular and threaded as at 45 to receive a closure cap 46. The base 47 has an internally threaded flange 48 to engage the threaded mouth of the container. An elongated plate 49 has a slot 50 through which the screw 51 is engaged to attach and adjust the same on the nozzle, and the plate has an end flange 52 to form a stop or rest to support the nozzle when filling a receptacle (not shown) from the container 1.

From the foregoing, it is believed that the operation and advantages of my invention will be apparent, but it is again pointed out that interpretation of the scope of my invention should only be conclusive when made in the light of the subjoined claims.

I claim:

1. A liquid dispenser, comprising an open mouthed liquid container, a dispensing device removably attached to the container over its mouth and having a base constituting a cap for the container, a liquid outlet nozzle on the base, an air inlet tube mounted on the base and leading into an air inlet conduit at the end of the liquid outlet nozzle, and a valve closure for the liquid outlet nozzle and the air inlet tube, said valve closure provided with means normally holding the valve in closed position, and means for holding the valve in open position, a portion of the length of the air inlet tube being spaced from

the liquid outlet nozzle and the actuating means for the valve being located between the air inlet and the liquid outlet.

2. The invention as defined in claim 1 wherein the valve has a stem supporting a cup and a spring bearing against the cup and base to hold the valve closed, and the valve having a circular head and sealing gasket both located in the mouth of the container.
3. The invention as defined in claim 1 wherein the means for holding the valve open includes a notched plate having a handle, and pivoted on the stem to engage the plate in notches on a rib on the nozzle to hold the valve open, or to register the notch on the plate with the rib to permit closing of the valve.

4. The invention as defined in claim 1 wherein the air inlet has a supplementary vent to relieve congestion in the air inlet in the event of clogging, and a valve for the vent.

5. The invention as defined in claim 1 wherein a spout having an air inlet and fluid outlet is removably attached to the nozzle.

6. A liquid dispenser comprising an open mouthed container, a dispensing device removably mounted over the open mouth and having a base formed with a threaded flange to engage the threaded mouth of the container, a fluid outlet nozzle formed on the base, an air inlet tube leading into the container through the base of the nozzle formed at the end with an air inlet conduit with which the tube is connected, a closure means including a spring-pressed valve for the nozzle and tube, means for holding said valve open including a plate pivoted on the stem of the valve and engaging the nozzle, an auxiliary air inlet on the air inlet tube, and means for opening the closure means.

WILLIAM E. TURNER.
